STEAM TRAP

Dean H. Brownell, Willoughby, Ohio, assignor to
 The C. E. Squires Company, Cleveland, Ohio,
 a corporation of Ohio

Application April 22, 1941, Serial No. 389,782

8 Claims. (Cl. 137—103)

This invention relates to steam traps, and more particularly to an improved construction for steam traps of the open-bucket type.

An object of my invention is to provide an improved steam trap, of the open-bucket type, which is of very simple and compact construction and which has the inlet and discharge connections in its top or cover so as to facilitate installation thereof.

Another object of my invention is to provide an improved steam trap in which valve means controlling the discharge opening is arranged to be actuated by an open-bucket movable upon a fixed guide.

A further object of my invention is to provide an improved steam trap of the open-bucket type having means for directing the flow of fluid through the trap so as to prevent the accumulation of sediment at the bottom of the chamber.

Still another object of my invention is to provide an improved steam trap having an open bucket movable on a hollow guide and in which the hollow guide has communication with the chamber of the casing adjacent the bottom thereof and with the bucket below the top rim thereof so as to cause fluid entering the bucket through the hollow guide to sweep over the bottom of the chamber and prevent the accumulation of sediment thereon.

My invention may be further briefly summarized as consisting in certain novel combinations and arrangements of parts hereinafter described and particularly set out in the appended claims.

In the accompanying sheets of drawings;

Fig. 1 is a vertical sectional view taken through a steam trap of my improved construction;

Fig. 2 is a similar sectional view taken through the trap but showing the bucket in its lower position;

Fig. 3 is a transverse sectional view taken through the trap as indicated by line 3—3 of Fig. 1;

Fig. 4 is a partial vertical sectional view on a larger scale, taken through the lower portion of the discharge tube to further illustrate the function of the valve actuating lever;

Fig. 5 is a vertical sectional view taken through a modified form of my improved steam trap;

Fig. 6 is a transverse sectional view taken through such modified form of trap as indicated by line 6—6 of Fig. 5;

Fig. 7 is an outside elevational view of my improved steam trap;

Fig. 8 is a vertical sectional view taken

through another modified form of my steam trap;

Fig. 9 is another vertical sectional view of this same device taken as indicated by line 9—9 of Fig. 8;

Fig. 10 is a vertical sectional view taken through still another modified form of my steam trap; and

Fig. 11 is a transverse sectional view taken therethrough as indicated by line 11—11 of Fig. 10.

Further reference will now be made to the drawings for the purpose of describing in greater detail the construction and operation of certain steam traps embodying my invention. Before proceeding with such more detailed description, however, it should be understood that my invention is not limited to the particular steam traps herein disclosed but may be embodied in various other similar devices.

As shown in Figs. 1 and 3, my improved steam trap is provided with a casing comprising a top or cover section 10 and a hollow body 11 connected with such top so as to extend in depending relation thereto. The hollow body and top define a working chamber 12 which houses the bucket 13 and the other working parts of the device.

To facilitate installation of my steam trap in pipe lines I locate the inlet and discharge openings 14 and 15 in the top or cover section 10 so that inlet and discharge pipes 16 and 17 connected with these openings can extend in substantial alignment with each other. The top 10 may have additional tapped openings 18 and 19 formed therein to permit inlet and discharge pipes 16 and 17 to be connected with the device in parallel relation to each other if this should be desirable. When the pipes 16 and 17 extend in substantially aligned horizontal relation, as shown in Fig. 1, the tapped openings 18 and 19 may be closed by screw plugs 20.

The bucket 13 is of the open type, but instead of being mounted for a pivoted or swinging movement as heretofore, it has a substantially vertical or straight-line movement in which it is guided by a headed guide member 21 depending from the top 10. The bucket may have a guide sleeve 22 therein which is slidable on the guide member 21 and provides an axial opening through the bucket.

The discharge opening 15 may be controlled by a valve 23 comprising a valve seat 23a and a movable valve element 23b and may communicate with the interior of the bucket 13 through a discharge tube 24. This discharge tube may be mounted on the top 10, or on the valve seat 23a,

so as to extend in depending relation from the top and downwardly into the bucket to a point adjacent the bottom of the latter. The lower end of the tube 24 is in open communication with the bucket and carries a transverse fulcrum pin 25, the purpose of which will be presently explained.

The valve element 23b may have an actuating stem 26 extending substantially axially of the discharge tube 24 and provided at its lower end with a forked head 27. A valve actuating lever 28 is located in the bucket 13 adjacent the bottom thereof and is arranged to swing on the fulcrum pin 25 of the discharge tube. The lever 28 may be pivotally connected adjacent one end thereof with the valve rod 26, as by the pivot pin 28a, and adjacent such pivot pin may have a hook-like portion 28b in pivotal engagement with the fulcrum pin 25 of the discharge tube 24. As shown in Fig. 3, the lever 28 has spaced arms 28c which straddle the guide sleeve 22 and are forked or slotted adjacent their outer ends, as indicated at 28d. The outer end of the lever 28 may be connected with the bucket 13 as by means of a transverse pin 29 which engages in the slots 28d and has relative sliding therein during swinging of the lever. The pin 29 may be suitably connected with the bucket as by being mounted in a bracket 30 which may be attached either to the guide sleeve 22 or the bottom wall, or both. If desired, a star-like guide element 31 may be mounted on the valve stem 26 adjacent its point of connection with the valve element 23b and may have slidable guiding engagement with the inner wall of the discharge tube 24 for centering the valve element with respect to the opening of the valve seat 23a.

The inlet opening 14 communicates with the working chamber 12 at a point above the bucket 13 and to prevent the incoming fluid from dropping directly into the bucket I provide a baffle 32 which deflects the fluid laterally beyond the side or rim of the bucket. This baffle may be in the form of a deflecting plate which may be connected to the underside of the cover 10 and may extend downwardly and outwardly with respect to the inlet opening.

In the operation of my improved steam trap, condensate and vapor enter the working chamber through the inlet opening 14, and as the condensate collects in the chamber, its level will rise and will cause the bucket 13 to be lifted, that is, to float, thereby closing the valve element 23b and preventing steam or vapor from passing through the trap. When the amount of condensate in the chamber 12 increases sufficiently it overflows the rim of the bucket 13 and filling the same causes it to sink. The downward movement of the bucket rocks the lever 28 on the fulcrum pin 25, causing downward movement of the valve rod 26 and opening of the valve element 23b. The pressure in the supply line 16 acting on the condensate causes a flow of the condensate out of the bucket and through the discharge tube 24 into the discharge pipe 17 whereupon the bucket 13 again rises or floats and thereby causes closing of the valve element 23b. It will be observed that during the downward movement of the bucket which causes swinging of the lever 28 on its pivot 25, this lever moves relative to the bucket from a position substantially parallel with its bottom, as shown in Fig. 1, to a relatively inclined position, as shown in Fig. 2.

I have provided for an increased leverage to be exerted by the lever 28 to forcibly open the 75

valve if there should be a tendency for the valve element 23b to stick to its seat. For this purpose I may provide the lever with a fulcrum pin 33 which is relatively closer to the pivot pin 25 than the fulcrum pin 25 of the discharge tube. I also provide the discharge tube with a surface or shoulder 34 against which the pin 33 will bear, as shown in Fig. 4, whenever the valve element sticks to its seat and the lever 28 tends to rock on the pivot pin 28a. The greater mechanical advantage afforded by the fulcrum pin 33 will insure separation of the valve element from its seat in response to downward movement of the bucket.

The hollow body 11 may, if desired, be provided with a drain or clean-out opening 35 in the bottom wall thereof and which may normally be closed by a screw plug 36.

In Figs. 5 and 6 I show a modified form of my improved steam trap in which provision is made for a sweeping flow of fluid across the bottom of the working chamber to remove sediment therefrom. This modified form of steam trap also comprises a top or cover section 40 and a hollow body 41 connected with the top in depending relation thereto. The top 40 is also provided with inlet and outlet openings 42 and 43, the latter of which is controlled by a movable valve element 44 similar to that employed in the trap of Fig. 1. The valve element 44 is provided with a stem 45 disposed substantially coaxially of a discharge tube 46 which depends from the underside of the top 40 and extends downwardly into the open bucket 47. A valve actuating lever 48, fulcrumed on the lower end of the discharge tube 46 and having pivotal connection with the valve rod 45 and the bucket, causes opening and closing of the valve element in response to movements of the bucket in the manner explained above.

In this modified construction the bucket 47 is movable on a hollow guide 50 which is carried by the top 40 and extends downwardly therefrom into the working chamber to a point adjacent the bottom thereof. The lower end of the hollow guide 50 is in open communication with the working chamber at a point adjacent the bottom thereof and the upper portion of the hollow guide is in communication with the interior of the bucket 47 through openings 51 formed in the guide. The bucket is provided with a guide sleeve 52 which is slidable on the hollow member 50 for guiding the bucket thereon and, as will be seen in Fig. 5, the sleeve 52 is somewhat lower in height than the side wall of the bucket so as to leave uncovered one or more of the openings 51.

When condensate collects in the device and flows into the bucket, either through the hollow guide 50 or by overflowing the rim of the bucket or both, it causes the bucket to sink thereby swinging the lever 48 downwardly and opening the valve element 44. The downward movement of the bucket 47 also causes the guide sleeve 52 to uncover one or more additional openings 51 of the hollow guide 50. The pressure on the condensate will cause the same to flow out of the bucket 47 through the discharge tube 46 while the valve element 44 is open. This pressure will cause additional condensate in the working chamber to flow upwardly through the hollow guide 50 and through the openings 51 into the bucket before passing out through the discharge tube 46. The upward flow of condensate through the hollow guide 50 will cause

the condensate surrounding the bucket to flow downwardly in a stream which will sweep across the bottom of the chamber before it flows upwardly into the hollow guide 50. This sweeping flow of the fluid across the bottom of the chamber will pick up or entrain sediment and will carry the same out of the device through the discharge opening. By providing the hollow guide 50 with an axially extending series of the openings 51 which are uncovered in succession as the bucket moves downwardly, it will be seen that an opening for the flow of liquid into the bucket will always be available at a point just above the top of the guide sleeve 52.

To augment this scavenging flow of fluid across the bottom of the working chamber I may provide a baffle 53 on the lower end of the hollow guide 50. This baffle may be in the form of a disk-like plate mounted on or adjacent the lower end of the guide so as to extend in adjacent substantially parallel relation to the bottom of the chamber. When this baffle is used it will be seen that condensate surrounding the bucket 47 must flow first downwardly and then laterally across the bottom of the chamber before it can pass upwardly through the hollow guide 50.

The inlet opening 52 communicates with the working chamber at a point above the bucket 47 and to prevent the fluid from dropping directly into the bucket I provide a downwardly and outwardly inclined baffle 54 for deflecting the incoming fluid laterally beyond the rim of the bucket.

In Figs. 8 and 9 I show a modified form of my self-cleaning steam trap which is similar to the trap of Figs. 5 and 6 but in which the open bucket 55 is guided by two laterally spaced depending hollow guide members 56 instead of a single hollow guide as in Fig. 5. The use of two such laterally spaced hollow guides has some advantages in that there is less likely to be tilting of the bucket which might result in sticking or jamming thereof. This is an important consideration in traps of the larger sizes. Another advantage is that the lever 57, which actuates the discharge valve 58 in response to movements of the bucket, can be a straight lever extending between the two guide tubes 56 instead of a forked lever, as shown in Fig. 6. When the two hollow guide tubes 56 are employed each tube is provided with a baffle plate 59 at the lower end thereof which serve the same purpose as described above for the baffle plate 53, and the bucket 55 is provided with two of the sleeves 52 which are slideable on the hollow guides. In all other respects the modified trap of Figs. 8 and 9 is similar to the trap illustrated in Figs. 5 and 6.

In Figs. 10 and 11 I have illustrated another form of trap which is similar in construction to the trap of Fig. 1 but in which the bucket 60 has two upright filling tubes 61 therein. These filling tubes may extend through the bottom wall of the bucket and have their lower ends in open communication with the lower portion of the working chamber 12 and have their upper ends in open communication with the interior of the bucket at a substantial distance below the top rim thereof. In all other respects the trap of Figs. 10 and 11 is similar to the trap illustrated in Figs. 1 and 3. When the level of condensate in the chamber 12 rises it will flow into the bucket through the filling tubes 61 instead of over the top rim as in the trap 75

of Fig. 1. When the bucket loses its positive buoyancy and sinks there will be an additional flow or surge of condensate from the lower portion of the chamber 12 up through the filling tubes into the interior of the bucket. Thus it will be seen that the provision of the filling tubes 61 will cause fluid to flow into the bucket from the lower portion of the chamber 12 instead of from the upper portion of the chamber and this will result in the fluid surrounding the bucket first flowing downwardly toward the bottom of the chamber and then upwardly through the filling tubes 61 whereby sediment will be swept from the bottom of the chamber and carried along by the fluid being discharged from the trap.

From the foregoing description and the accompanying drawings it will now be readily understood that I have provided an improved steam trap of the open-bucket type which is very simple and compact and which can be made much lighter in weight than the traps of this type heretofore provided. The decreased weight and the arrangement of the inlet and outlet openings in substantial alignment in the top of the device facilitate the work of installing the trap and in many instances make it possible to install the trap without need for a shelf or other auxiliary support. It will further be seen that my improved trap also provides for a scavenging flow of fluid which will remove sediment from the bottom of the working chamber.

While I have illustrated and described my improved steam trap construction more or less in detail, it will be understood, of course, that I do not wish to be limited to the particular details of construction and arrangements of parts herein disclosed, but regard my invention as including such changes and modifications as do not constitute a departure from the spirit of the invention and the scope of the appended claims.

Having thus described my invention, I claim:

1. In a steam trap, a casing having inlet and discharge openings, a hollow guide depending in said casing, a valve controlling the discharge opening, an open bucket movable on said guide and having operative connection with said valve to actuate the latter, and a discharge tube connected with the discharge opening and extending down into said bucket, said hollow guide forming a passage for the flow of condensate from the casing into the bucket and having communication with the chamber of said casing adjacent the bottom thereof and with said bucket at a point below its top rim so that upon the opening of said valve condensate will flow upwardly from the bottom of the casing into the bucket through said passage and then out of the bucket through said discharge tube.

2. A steam trap comprising a casing having inlet and discharge openings, a hollow guide depending in the casing, a valve controlling the discharge opening, an open bucket movable on said guide and having operative connection with said valve to actuate the latter, a discharge tube connected with the discharge opening and extending down into said bucket, said hollow guide forming a passage for the flow of condensate from the casing into the bucket and having communication with the chamber of said casing adjacent the bottom thereof and with said bucket at a point below its top rim so that upon the opening of said valve condensate will flow upwardly from the bottom of the casing into

the bucket through said passage and then out of the bucket through said discharge tube, and a baffle arranged adjacent the bottom of the chamber so as to cause fluid entering said hollow guide to sweep over the bottom of the chamber.

3. A steam trap comprising a casing having a top provided with inlet and discharge openings, a hollow guide depending from said top, a valve controlling the discharge opening, an open bucket having operative connection with said valve to actuate the same and also having therein a guide sleeve slidable on said hollow guide and which is of less height than the side wall of the bucket, and a discharge tube connected with the discharge opening and extending down into said bucket, said hollow guide forming a passage for the flow of condensate from the casing into the bucket and having its lower end in communication with the chamber of the casing at a point adjacent the bottom thereof and also having an opening into the bucket at a relatively higher point adapted to be uncovered by said sleeve so that upon the opening of said valve condensate will flow upwardly from the bottom of the casing into the bucket through said passage and then out of the bucket through said discharge tube.

4. In a steam trap, a casing having inlet and discharge openings and a working chamber, a valve controlling the discharge opening, an open-top bucket having guided substantially straight-line movement in said chamber and having operative connection with said valve to actuate the latter, a tube connected with the discharge opening and extending down into said bucket, and means providing a passage connecting the lower part of said chamber with the bucket and communicating with the latter at a point above its bottom but below its top rim so that upon the opening of said valve condensate will flow upwardly from the bottom of the casing into the bucket through said passage and then out of the bucket through said discharge tube.

5. In a steam trap, a casing having inlet and discharge openings and a working chamber, a valve controlling the discharge opening, an open-top bucket having guided movement in said chamber and having operative connection with said valve to actuate the latter, and a discharge tube connected with the discharge opening and extending down into said bucket, said bucket having therein an upright filling tube providing a passage communicating with the lower portion of said chamber and with the interior of the bucket a substantial distance below its top rim so that upon the opening of said valve condensate will flow upwardly from the bottom of the casing into the bucket through said passage and then out of the bucket through said discharge tube.

6. A steam trap comprising a casing having a top and a hollow body connected with said top and depending therefrom, said top having inlet and outlet openings therein, a depending guide member connected with the top, an open bucket slidably guided on said guide member for substantially straight-line movements in said

casing, a discharge tube connected with said top so as to communicate with the outlet opening and extending down into said bucket, a valve controlling said outlet opening and having an actuating stem, a lever fulcrumed on said tube and having operative connection with said stem, a pin-and-slot connection between said bucket and lever for actuating the latter in response to said substantially straight-line movements of the bucket, and a filling passage leading into the bucket at a point above its bottom but below its top rim and communicating with the lower portion of said casing so that upon the opening of said valve condensate will flow upwardly from the bottom of the casing into the bucket through said passage and then out of the bucket through said discharge tube.

7. A steam trap comprising a casing having fluid inlet and outlet openings, a hollow guide member depending in said casing from the top thereof, an open bucket having a sleeve slidably guided on said guide member for limiting the bucket to substantially straight-line movements in said casing, a discharge tube connected with said outlet opening and extending down into the bucket adjacent one side thereof, a valve controlling said outlet opening, a lever fulcrumed on said tube and cooperating with said valve, a pin-and-slot connection between the bucket and lever and located adjacent the opposite side of the bucket, said hollow guide having its lower end in communication with the chamber of the casing at a point adjacent the bottom thereof and also having an axially extending series of openings arranged to be uncovered in succession by said sleeve during downward movement of the bucket so that upon the opening of said valve condensate will flow upwardly from the bottom of the casing into the bucket through said passage and then out of the bucket through said discharge tube, and a baffle plate carried by the lower end of said guide member and arranged to cause the condensate entering said hollow guide to sweep over the bottom of the casing.

8. A steam trap comprising a casing having a top provided with inlet and discharge openings, a hollow guide depending from said top, a valve controlling the discharge opening, an open bucket having operative connection with said valve to actuate the same and also having a guide sleeve slidable on said hollow guide and which is of less height than the side wall of the bucket, and a discharge tube connected with the discharge opening and extending down into said bucket, said hollow guide having its lower end in communication with the chamber of the casing at a point adjacent the bottom thereof and also having an axially extending series of openings arranged to be uncovered in succession by said sleeve during downward movement of the bucket so that upon the opening of said valve condensate will flow upwardly from the bottom of the casing into the bucket through said passage and then out of the bucket through said discharge tube.

DEAN H. BROWNELL.
